(57) **CLAIM**

I claim the ornamental design for a guitar pick, as shown and described.

DESCRIPTION

FIG. 1 is a front perspective view of a guitar pick, showing my new design;

FIG. 2 is a rear perspective view thereof;

FIG. 3 is a front elevational view thereof;

FIG. 4 is a rear elevational view thereof;

FIG. 5 is a right-side elevational view thereof;

FIG. 6 is a left-side elevational view thereof;

FIG. 7 is a top plan view thereof; and,

FIG. 8 is a bottom plan view thereof.
